FUR WETTING APPARATUS

Jacob Morgenstern, Brooklyn, N. Y.

Application May 15, 1943, Serial No. 487,132

6 Claims. (Cl. 69—29)

This invention relates to fur pelt conditioning apparatus, and more particularly to means for uniformly wetting the skin side of a fur pelt.

During the process of preparing a fur pelt for incorporation into a garment, it is necessary to thoroughly wet the skin or leather side of the fur pelt in order that the pelt may be properly stretched for assembling with other pelts into such garment. If the skin side of the pelt is not thoroughly and uniformly wet, difficulty is experienced in utilizing the full area of the pelt as full stretch of the skin is not obtainable. Naturally, this would result in wastage.

Hitherto, this wetting operation has been performed manually by placing the pelt on a support with its fur side downward and then rubbing water into the skin or leather side of the pelt by means of a brush. It has been impractical by the manual operation to obtain uniform irrigation or wetting of the skin side of the pelt. This required additional time for absorption of the water, and necessitated wringing of each individual pelt to remove excess water. The only alternative was to permit the pelt to soak for several hours, and in such soaking the fur side also became wetted, which is undesirable as it affects the appearance and quality of the fur, and necessitates additional time for drying the pelt.

If the garment is made overwet, it becomes dry and crunchy, rather than pliable. It is therefore difficult to nail the pelt to designated shape. Furthermore, some dampness is left on the surface of the pelt as all the water does not enter the pores thereof. This frequently caused skipping or breaking of needles during the sewing process.

It is therefore among the objects of this invention to provide apparatus for uniformly and controllably wetting the skin or leather side of a fur pelt; to provide such apparatus having means for forcing water into the pores of the skin side of the pelt; to provide such apparatus including means for applying a regulated amount of water to the skin side of a fur pelt and means for insuring a substantially uniform penetration of the water into the pores of the skin side of a fur pelt; to provide such apparatus including means for insuring thorough and uniform wetting of the skin side of a fur pelt while protecting the fur side of the pelt from moisture; and to provide such apparatus in which the component parts may be easily disassembled for inspection, repair or replacement.

These and other objects, advantages and features of the invention will be apparent from the following description and accompanying drawings. In the drawings:

5 Fig. 1 is a side elevational view of apparatus embodying the principles of the invention.

Fig. 2 is a vertical sectional view through the apparatus shown in Fig. 1.

10 Fig. 3 is a top plan view of the apparatus shown in Fig. 1.

Fig. 4 is a vertical sectional view on the line 4—4 of Fig. 3.

15 Fig. 5 is a partial elevational view of the side of the apparatus opposite to that illustrated in Fig. 1.

Generally speaking, according to the present invention, the pelt is passed through a pair of feed rolls so that its leather or skin side is brought adjacent a rotating brush. Water is supplied to 20 the rotary brush at a regulated rate, and the brush forces the water into the pores of the leather or skin side of the pelt. Uniform application of water to the skin side of the pelt results, and the amount and penetration of the wetting 25 can be controlled by varying the rate of flow of water to the brush and by varying the pressure with which the bristles of the brush engage the skin side of the pelt. Suitable means are provided for regulating the flow of water and for regulating 30 the pressure with which the brush engages the skin side of the pelt. Other means are provided for draining the used water from the vicinity of the brush and for straining foreign particles therefrom.

35 Referring more particularly to the drawings, the apparatus comprises a frame 10, included uprights 11, 11 and cross members 12, 13 and 14. A pair of brackets 15 are supported on the cross member 14 and serve as supports for the bearings for the rotary brush and the feed rolls. A pair of brackets 16 secured to the forward ends of the brackets 15 support a work or feed table 17. The pelt 18 is placed on the table 17 with its fur side down on the table and is fed into the machine by feed rolls 19 and 20. The feed roll 19 is provided with trunnions 21 mounted in bearings 22 which are slidably mounted in guides 25 formed on the bracket 15. The feed roll 20 is provided with trunnions 23 mounted in bearings 24. Springs 26 extend between the upper side of brackets 24 and spring seats 27. Adjustment of the pressure of the springs 26 is accomplished by suitable adjusting means such as a 50 screw 28 provided with a lock nut 29. The roller 55

19 may be lifted from a position adjacent the roller 20, and against the force of spring 26, by means of levers 30 pivoted at 31 on the bracket 15, and connected by links 32 to a treadle 33 adjacent the lower end of the frame 10. The treadle 33 is provided with cut-away portions 34 which slidably engage the forward vertical supports 11 to guide the treadle in its vertical movement.

As the pelt 18 passes through the feed rolls 19 and 20, its leather or skin side is engaged by bristles 39 of the rotary brush 40, which is mounted in bearings 41 and 42 which are adjustable longitudinally of the frame 10. For this purpose, a pair of pins 43 are slidably mounted in the bracket 15 and provided with collars 44 engaged by springs 45. The opposite ends of the springs 45 contact a block 46 forming part of each bracket 15. The forward ends of the pins 43 are pointed as at 47, and extend into conical recesses 48 in the bearings 41 and 42. The bearings 41 and 42 are also formed with conical recesses 49 diametrically opposite the recesses 48 and these recesses are engaged by the pointed ends 50 of threaded pins 51. The pins 51 are each threaded through upstanding ears or lugs 52 on the brackets 15 and are held in adjusted position by means of lock nuts 53.

The described construction permits adjustment of the distance between the ends of the brush bristles 39 and the feed roll 20, and thereby of the pressure with which the brush bristles 39 engage the skin side of the pelt 18. Furthermore, the described construction permits of ready removal of the rotary brush 40 from the apparatus for the purpose of cleaning, repair or replacement. To remove the brush 40, it is merely necessary to urge the same forwardly against the pins 43 until the bearings 41 and 42 are clear of the pins 51. The brush can then be easily removed from the apparatus, without disturbing the preset adjustment of the pins 51.

A trough 55 is mounted on and between the horizontal supports 14 and formed with an open faced extension 56 which extends down to a point below the horizontal members 13. The trough 55 is provided with a hood 57, which is hinged to the trough as at 58 so that it may be swung out of position to permit removal or inspection of the brush 40.

The brush 40 is supplied with water from a perforated pipe 60 mounted in the upper portion of the hood 57. The pipe 60 is supplied with water from a supply pipe 61 through a regulating valve 62 from which two branches 63 and 64 conduct water to the pipe 60. The provision of the two branches 63, 64 assures an even distribution of water to the pipe 60. The amount of water discharged by the pipe 60 is controlled by the valve 62, and for ready adjustment this valve may be provided with a dial 65 and a pointer 66. The supply pipe 61 is preferably made flexible to permit the hood 57 to be swung back on its hinges 58. Water from the trough 55 is discharged through a drain pipe 68 into a drain tank 69 mounted on the horizontal members 12. The drain tank 69 is provided with a sump pump 70 operated by a motor 71 which is controlled by a float 72. Water from the drain tank 69 is discharged through an outlet pipe 73. Such an arrangement is generally necessary in lofts where the apparatus of the invention may be used, due to the fact that the drain pipes in such lofts are usually located at ceiling level rather than at the floor level. However, if the location where the apparatus is installed is pro-

vided with a low level drain, the sump pump 70 will not be necessary, and an ordinary outlet pipe to the main drain may be substituted.

The feed rolls 19 and 20 and the brush 40, 5 are driven by a motor 75 mounted on the horizontal supports 12. The motor 75 is provided with a pulley 76 which drives a pulley 77 on the trunnion 78 of brush 40 through a belt 79. The opposite trunnion 80 of the brush 40 is provided 10 with a grooved pulley 81 which is connected by a belt 82 to a larger grooved pulley 83 mounted on a shaft 84 supported in bearings on the cross member 13. Also, fixed to the shaft 84 is a drive sprocket 85 connected by a chain 86 to a drive sprocket 87 fixed to the trunnion 23 of feed roller 20. Belt 82 is crossed between the pulleys 81 and 83 in order to reverse the direction of rotation of these pulleys.

Through the described arrangement, the motor 75 drives the brush 40 which in turn drives the pulley 83 and shaft 84 in reverse direction, causing the sprocket 85 to drive the sprocket 87 associated with the feed roller 20. The relative rotation of the feed rollers 19 and 20 and the brush 40 is in the direction indicated by the arrows of Fig. 2. On its opposite trunnion, roller 20 is provided with a large toothed gear 90 meshing with a similar gear 91 secured to the trunnion 21 of roller 19. The roller 20 thus drives the roller 19 in a reverse direction, and the relatively large teeth on the gears 90 and 91 permit meshing of these gears over a considerable variation in spacing of the rolls 19 and 20. The water dripping from the skin side of the pelt as it comes from between the brush 40 and the roller 20 is collected in a drip pan 93 formed on the lower portion of the extension 56 of trough 55, and the drip pan is connected by a drain pipe 94 to the drain tank 69. A screen 95 preferably is provided on the drip pan to catch any foreign particles which may fall from the skin side of the pelt 18.

In operation, the treadle 33 is depressed a sufficient amount to permit the pelt 18 to be slid over the table 17 and between the feed rollers 19 and 20, with its fur side placed downwardly upon the table 17. The water supply is then turned on through the valve 62, and the motor 75 is energized to rotate the brush 40 and the feed rolls 19 and 20. The feed rollers move the skin side of the pelt against the bristles 39 of the rapidly revolving brush 40 which thereupon uniformly forces water into the skin side of the pelt, and thoroughly wets the same to the desired extent. Preferably, the bristles 39 are made of fiber or animal matter as these hold the water better for brushing, and avoid scratching of the skin, as distinguished from wire bristles. The bristles also may be made of synthetic fiber, such as "nylon."

To insure uniform action of the brush 40 on the pelt 18, the bristles 39 are arranged in clusters which are spaced uniformly over the surface of the rolls, and the bristles are uniform in length. In one embodiment, the bristles are one inch in length and the clusters are spaced one-half inch apart on the roll. To assure uniform wetting of the bristles, the apertures 60' in the pipe 60 are uniformly spaced at close intervals throughout the length of the pipe, and are made with a very fine drill. In one embodiment, the apertures 60' are spaced one-half inch apart, and substantially aligned with the bristle clusters.

The described apparatus reduces the time of the wetting operation by 50% or more, and by proper adjustment will force water into the pores

of the skin side of the pelt leaving the surface in a condition equivalent to that of a skin permitted to soak for several hours. Uniform application of water to the skin side of the pelt is assured at all times, which makes the skin instantly suitable for handling by the cutter and operator, with no need for allowing time for absorption of the water or for wringing each individual skin to absorb excess water. The uniform application of water over the entire area of the skin side of the pelt improves the stretch of the pelt, in contrast to manual application of the water which may leave some portions of the pelt poorly irrigated. Furthermore, such uniform wetting assures full stretch of the skin, permitting the cutter to utilize every inch of material most efficiently with minimum effort and time.

As there is very little surface dampness due to most of the water entering the pores of the skin side of the pelt, the skipping or breaking of needles is greatly reduced. While the garment is not made overwet, which is very likely when the irrigating operation is done by hand, it is thoroughly wetted to a point sufficient to make it pliable and easy to nail to designated shape. In the case of extra large pelts, they may be doubled over with their fur side inwardly, and first one skin side surface wetted, and then the other skin side. Wetting of the fur part of the pelt is avoided by the present apparatus.

While a specific embodiment of the invention has been described in detail to illustrate the principles of the invention, it will be obvious to those skilled in the art that the invention may be otherwise embodied without departing from the scope of such principles.

What is claimed is:

1. Apparatus for uniformly wetting the skin side of a fur pelt comprising a frame; a rotary brush mounted on said frame; a trough mounted on said frame beneath said rotary brush; a hood hingedly secured to said trough above and covering said rotary brush; valve means secured to said hood for supplying water by gravity to said rotary brush at a regulated rate; flexible means for supplying water to said valve means; means for feeding the skin side of the pelt against said rotary brush; and gravity means for discharging excess water from said trough.

2. Apparatus for uniformly wetting the skin side of a fur pelt comprising a frame; a rotary brush mounted on the upper part of said frame; valve means for supplying water to said rotary brush at a regulated rate; means for supplying water to said valve means; a pair of feeding rollers mounted on the upper part of said frame for feeding the skin side of the fur pelt against said rotary brush; resilient means normally urging one of said rollers toward the other; and means for moving said rollers apart to permit insertion of a pelt therebetween including a pair of levers pivotally mounted on the upper part of said frame and engaging one of said rollers, a treadle slidably mounted on the lower part of said frame and links connecting said levers to said treadle.

3. Apparatus for uniformly wetting the skin side of a fur pelt comprising a frame; a rotary brush mounted on the upper part of said frame; valve means for supplying water by gravity to said rotary brush at a regulated rate; means for supplying water to said valve means; means for feeding the skin side of the pelt against said rotary brush comprising a pair of feeding rollers

mounted on the upper part of said frame and a work table mounted adjacent said rollers; a trough having a main portion mounted on said frame beneath said rotary brush and an extension beneath said work table; a drain tank mounted on the lower part of said frame; and means connecting said trough main portion and said extension to said drain tank to discharge excess water thereinto by gravity.

10 4. Apparatus for uniformly wetting the skin side of a fur pelt comprising a frame; a pair of bearings mounted on the upper part of said frame; a pair of adjustable abutments mounted on said frame and engaging one side of said bearings; a pair of spring pressed abutments mounted on said frame and engaging the opposite side of said bearings; a rotary brush mounted in said bearings; means for feeding the skin side of the pelt against said rotary brush; a hood hingedly secured to said frame; and means for supplying water to said rotary brush at a regulated rate comprising a perforated pipe secured inside said hood and aligned above said brush, a pair of oppositely extending branch pipes mounted on said hood and connected to said perforated pipe, a valve connecting said branch pipes and flexible means for supplying water to said valve.

5. Apparatus for uniformly wetting the skin side of a fur pelt comprising a frame; a pair of bearings mounted on the upper part of said frame; a pair of adjustable abutments mounted on said frame and engaging one side of said bearings; a pair of spring pressed abutments mounted on said frame and engaging the opposite side of said bearings; a rotary brush mounted in said bearings; means for feeding the skin side of the pelt against said rotary brush; a hood hingedly secured to said frame; and means for supplying water to said rotary brush at a regulated rate comprising a perforated pipe secured inside said hood and aligned above said brush, a pair of oppositely extending branch pipes mounted on said hood and connected to said perforated pipe, a valve connecting said branch pipes and flexible means for supplying water to said valve, said valve being provided with a dial and a pointer for ready regulation of the flow of water.

50 6. Apparatus for uniformly wetting the skin side of a fur pelt comprising a frame; a rotary brush mounted on the upper part of said frame; valve means for supplying water to said rotary brush at a regulated rate; means for supplying water to said valve means; a pair of cooperating feeding rollers mounted on the upper part of said frame; a work table mounted adjacent said rollers and having an upper surface aligned with the intersection of said rollers; a motor mounted on the lower part of said frame and provided with a drive pulley; a large pulley secured to one end of said rotary brush; a small pulley secured to the other end of said rotary brush; gear means interconnecting said rollers; driving means connecting said motor drive pulley to said large brush pulley; relatively large pulley means mounted on an intermediate portion of said frame; a sprocket secured to said pulley means; driving means connecting said small brush pulley to said pulley means; a sprocket secured to one of said rollers; and driving means interconnecting said sprockets.

JACOB MORGENSEN.
